APPLICATOR STICK

Solomon Ager, Bronx, N. Y.

Application September 5, 1947, Serial No. 772,320

1 Claim. (Cl. 128—269)

1

This invention relates to applicator sticks used in surgical treatments of the body.

It is an object of the present invention to provide an applicator stick which can be broken to form two separate applicator sticks by a clean break of the same at a weakened section of the stick and at the middle of the original applicator stick and wherein there will be provided, adjacent said weakened section, indentations, barbs or projections for the purpose of maintaining upon the stick a plegget of cotton which may be wound upon the same and which will prevent the removal of the cotton upon the end of the stick while the stick is being used in the treatment of the body.

Other objects of the present invention are to provide a separable applicator stick which can be divided into two sticks without the same being split at the break ends, which is of simple construction, inexpensive to manufacture and convenient to use.

For a better understanding of the invention, reference may be had to the following detailed description taken in connection with the accompanying drawing, in which

Fig. 1 is a perspective view of my applicator stick part which has been severed,

Fig. 2 is a longitudinal sectional view taken generally on line 2—2 of Fig. 1,

Fig. 3 is an enlarged perspective view of one stick having a knurled formation thereon to retain the cotton,

Fig. 4 is an enlarged perspective view of the end of the stick on which barbs are formed to retain cotton,

Fig. 5 is an enlarged perspective view of a stick end which has been formed by cutting the surface of the stick,

Fig. 6 is a side elevational view of the single applicator stick from which the two divided sticks are made, with the weakened portion being in the middle and with the roughened portion lying adjacent to the weakened section and adapted to receive cotton,

Fig. 7 is a fragmentary and enlarged view of the middle of the initial stick and looking upon the weakened section thereof.

Referring now to the figures and more particularly to Figs. 6 and 7, there is shown a single applicator stick 10 from which separate sticks may be made by bending as illustrated on dotted lines

2

in Fig. 6 so that the stick will break in the region of its weakened portion 11 to form separate sticks 12. Adjacent to the weakened section 11 are roughened portions 13 about which cotton can be extended and retained as the stick is used. The section 11 can be formed by rolling or cutting a groove into the applicator stick at the middle of the same. Accordingly, when the stick is bent, it will break at the weakened section 11 and this break will be clean and free of loosened splinters. The outer ends of the stick will also have a roughened portion 13 so that the cotton as indicated at 14 can be connected at either end of the stick 10 or at either end of a divided stick 12.

The usual stick is smooth at its end and does not retain very well the plegget of cotton. Even though the stick is made of wood and has a tendency to be somewhat rough it does not fully or adequately retain the cotton on the stick. The roughened portion 13 can be formed in different ways as by crushing to splinter the wood at its surface so as to provide notches or indentations therein, as illustrated in Fig. 5. The surface of the stick will be splintered to some extent so as to catch the fine fibers of the cotton.

The stick may be knurled as shown in Fig. 3 so as to provide diagonally extending notches 15 over the surface and raised portions 16. The cotton will fill the diagonal notches 15 and will be restrained thereon by abutment with the raised portions 16.

If desired the portion 13 can be formed by barbing the end of the stick to provide barbs 17 thereon, arranged in circular rows with the barbs of alternate rows offset respectively with the barbs of the rows therebetween. The barbs will accordingly be staggered with respect to one another throughout the length of the portion.

If the user of the stick does not require for his operation the full applicator stick 10 and can use a shorter stick or desires to be economical in the use of the sticks because of a shortage of supply, the usual applicator stick 10 can be broken in two at the weakened section 11 and two applicator sticks will be formed. Each of the two applicator sticks will have roughened portions at both ends of the stick. The only difference between the divided stick and the original stick is, that it is shorter.

The projections may consist of one or various

combinations of the above or together with any other geometrical shapes and designs.

While various changes may be made in the detail construction, it shall be understood that such changes shall be within the spirit and scope of the present invention as defined by the appended claim.

I claim:

An applicator stick having rough portions at the opposite ends of the same to retain cotton thereon against slippage, a weakened section intermediate the length of the stick to permit a clean break of the stick in two and to provide two applicator sticks, and roughened portions adjacent the weakened section and at opposite sides

thereof whereby to provide sticks when the break has been made with roughened portions at the opposite ends of the same.

SOLOMON AGER.
